POCKETED LEAF FOLDER

Arne G. Fredriksson, Sabbatsvagen 3, S-175 40
Jarfalla, Sweden

Filed Sept. 19, 1973, Ser. No. 399,251

Claims priority, application Sweden Mar. 27, 1973

Term of patent 14 years

Int. Cl. D19—04

U.S. Cl. D19—33

The figure is a perspective view of a pocketed leaf folder showing my new design. The surface not shown is plain and unornamented.

I claim:

The ornamental design for a pocketed leaf folder, as shown and described.
